United States Patent Office

Des. 227,136
Patented June 5, 1973

227,136

GOBLET

Adolf Kies, 8903 Balboa Blvd.,
Northridge, Calif. 91324

Filed Feb. 14, 1972, Ser. No. 226,389

Term of patent 14 years

Int. Cl. D7—01

U.S. Cl. D44—9 B

Fig. 1.

1
2

Fig. 2.

FIG. 1 is a perspective view of a goblet showing my new design; and

FIG. 2 is a cross-section view on line 2—2 of FIG. 1 in the direction of the arrows.

I claim:

The ornamental design for a goblet, substantially as shown.
